UNITED STATES PATENT OFFICE

1,992,694

FILING DEVICE

James H. Field, Washington, D. C.

Application July 14, 1933, Serial No. 680,469

13 Claims. (Cl. 129—16)

This invention relates to improvements in filing devices; and more particularly, to devices in which a plurality of partitions or separator members are supported in a substantially vertical position with flexible elements extending through openings or slots formed in the lower portion of the partitions.

In devices of the type described, it is customary to have the partitions slidably mounted on rails or frames and the flexible elements. This type of construction is open to the objection that when the pockets formed by the partitions are only partly filled, a sudden movement of the drawer in opening will have a tendency to dislodge the pockets and their contents from the filed position, spreading the partitions and necessitating that the file clerk or other person reassemble the file in its proper position. This is particularly true when the rear of the file has been filled with heavy flexible material. Therefore, it becomes necessary to provide means for efficiently holding the partitions in position when the file is only partially filled. These means must be simple, inexpensive, and applicable in the least time and with the least effort.

The principal object of my invention, therefore, is to provide means for maintaining the partitions when partly filled in a predetermined position in relation to the remainder of the file so that accidental displacement is reduced to a minimum.

Another object of the invention is to provide means for regulating the tension of the flexible elements or strips which extend through the partitions both longitudinally and angularly.

Other objects will be disclosed in the specification and claims forming a part of this application.

Figure 1 is a bottom perspective of the filing frame, showing the movement of the spacer and flexible strips in dotted lines;

Figure 2 is a vertical longitudinal section;

Figure 3 is a fragmentary top plan showing the spacing means at the front;

Figure 4 is a detailed perspective of the spacer member;

Figure 5 is a modified form of the spacer member;

Figure 6 is a vertical cross section taken on line 6—6 of Figure 7 showing a modified form of the securing means;

Figure 7 is a vertical section taken on line 7—7 of Figure 6;

Figure 8 is a fragmentary perspective of the modified form of frame and spacing means;

Figure 9 is a modified fragmentary perspective of the frame and securing means;

Figure 10 is a top plan of a modified form of the invention in which no side rails other than the sides of the drawer are used;

Figure 11 is a detailed perspective taken on line 11—11 of Figure 10;

Figure 12 is a vertical cross section of a modified form of the invention; and

Figure 13 is an exploded perspective of a spacing strip shown in Figure 12.

Referring to the drawings in which similar parts are designated by like numerals:

Numerical 14 designates, as shown in Figure 1, a pair of supporting rails arranged substantially horizontally on which are suspended a series of separator partitions 15 having side projections at the upper corners with slotted openings 16 which loosely engage the rails 14.

The rails 14 are provided with downwardly extending arms 17 at each end, the pair of said arms at each end being joined together by bottom members 18. One or more flexible elements or strips 19 are connected at each end to the bottom member 18 in such a way that the resiliency of the

four spring corners where the rails are bent down to form legs keep the strips 19 under tension at all times. The bottom portions of the partitions 15 are provided with slots or openings 20 which slidably engage the strips 19 so that the bottom

of the partitions 15 are free to move longitudinally of the strips 19. Formed on the bottom members 18 are ferrules 21 which serve to receive the ends of the frame members and likewise to space the flexible strips 19 apart when in normal position.

Connected to the rear bottom member 18 by a ring 22 is a spacer strip 23 having notches 24 adapted to receive the flexible strips 19 and separate the same so as to force the strips 19 into frictional contact with the outer edges of the

openings 20.

Elastic connectors 20' are attached to each partition. Making these connectors elastic is possible due to the limiting of movement of the active part of the file, whereas previously it was necessary to use cords or other non-elastic material. Further, having the connectors elastic facilitates the expansibility of the space between the pockets and retracts to a normal position when lightly filled.

As actually used, the filing device as illustrated in the preferred form shown in Figure 1, forms a self-contained unit adapted to be inserted in a file drawer 25 as shown in Figure 2.

The details of construction and advantages are

clearly illustrated and claimed in the Field Patent No. 1,901,365, issued March 14, 1933.

As previously pointed out, filing units of the type illustrated in the said Field patent, are objectionable in that when partially filled and a sudden movement is given the same upon opening by the file clerk, there is a tendency for the partitions to become disarranged and the contents displaced. By placing the spacer strip 23 between the flexible strips 19, sufficient tension or friction is created in connection with the partitions so that accidental displacement is reduced to a minimum.

I have found that after the filing unit is filled and the partitions approach the capacity of the unit, there is sufficient friction due to the weight and expansibility of the contents of the file to prevent this objectionable displacement of the files. As this point is reached, the clerk need only disengage the spacer strip 23 from the flexible strips 19 and use the file unit in the usual manner. The manipulation of the spacer strip is very simple and requires no attention other than the initial spacing operation and the removal of the strip from contact with the flexible members at the desired time. It is not necessary that the spacer strip 23 be secured to the frame as these strips may be used separately, but by having the same secured to the bottom member 18, there is no danger of the same becoming lost when not in use.

I do not intend to limit myself to use of my invention where resilient rails and arms are used, as it is obvious that the invention is equally as valuable where the partition members 15 hook over and rest on the sides 26 of the file drawer 25, as illustrated in Figure 10.

I also do not wish to limit myself to the particular embodiment of spaced strip 23 as shown in Figure 1. The same problem will occur whenever separator partitions or pockets are slidably mounted on flexible elements.

In Figure 3 the spacer strip 23 is shown at the front of the drawer 25 as under many systems the filing starts at the rear and works forward. It is obvious also that spacer strips can be used both at the rear and the front where it is desired to file in the center.

Figure 5 shows the indents 24' formed in the top of the strip instead of at the ends so as to afford a graduated frictional tension. This form of strip is adapted to be used where a rod is used extending the length of the container to prevent the pulling out of the conventional guides.

It is obvious that there will be a certain amount of permanent lengthening where flexible strips are used, and so in Figures 6 and 7 buckles 26 are shown, in connection with the flexible strips 19, the strips passing under the rear bottom member 18 and being provided with metal or otherwise rigid U-shaped end members hooked over the edge 27 of the drawer 25.

On top of the rear edge 27 of the drawer 25 are positioned screws 28 to space the flexible strips apart and bring the same into angular contact with the partitions 15. The buckles 26 serve to not only keep the strips 19 under tension, but are highly desirable where a resilient frame is used, as illustrated in Figure 7. When it is no longer necessary to angularly displace the flexible strips 19 in the modified form shown in Figures 6 and 7, the strips will be lifted over the screws 28 and moved into alignment with the openings in the partitions 15.

As shown in Figures 8 and 9, the spacer strip

23 is eliminated and shoulders 29 or indents 30 are formed in the bottom member 18. In the case of the shoulder 29 shown in Figure 8, the bottom member 18 gradually tapers to form the shoulder 29.

In Figure 10 no rails or arms are utilized, the flexible strips 19 being secured to a securing member 31 in front of the drawer by way of buckles 26 and at the rear of the drawer is arranged a series of hooks 32, the strips 19 having eyelets 33 formed in the ends to fit over the hooks 32 in accordance with the necessary amount of angular displacement in order to create proper friction between the strips 19 and the partitions 15.

Figure 13 is a modified form of the spacing strip 23 in that it is divided into halves 34 and 35 which overlap each other, having elongated slots 36 to receive a wing bolt 37. The angular displacement of the flexible strips 19 may readily be increased or decreased by movement of the overlapping halves 34 and 35. Figure 12 shows this modified form of strip in position.

It will be apparent from a reading of the foregoing specification that in certain stages of filing where the structure used is similar to that described in my Patent No. 1,901,365, the filing space between the front of the container and the partition is not sufficiently restrained, particularly when only partly filled with heavy flexible material. By spreading the normal parallel flexible strips and maintaining them angularly spaced, the partitions can only recede from the front of the container against a progressively increasing resistance of the strips against the outer edges of the holes in the outer partitions. As the active filing space is filled and the other partitions forced against the angular position of the strips, the angle of distortion will become greater and the amount of parallel strip longer. The file clerk becomes aware of this by the increasing difficulty of moving the partitions against the angular displacement. By the time the container approaches being filled, the partitions and contents therein become stabilized and stand substantially vertically throughout the container. This is equally true if a spacer strip is used in front. Upon the point of stabilization being reached, the file clerk will either remove the spacer strip or adjust it to relieve the acute tension.

The use of the spacer member, or any means for spreading the flexible strips, not only forms a cushioning resistance to the enlargement of the file space in front of the partition, but assures a constant tension in the parallel parts of the flexible strips which gives an even resistance to the V-ing or swinging of the partitions when operated by the hand of the file clerk for filing purposes. The spreading of the flexible strips offers a progressive and automatically increasing resistance to the enlargement of the filing space.

The flexible material used in the strips 19 is, of course, capable of stretching, although it is not elastic. This stretchability of the material is actually utilized in practice as it enables the partitions to recede further before the spacer must be removed. At the same time the tensioning of the flexible strips by the spacer strip not only impedes the progressive movement of the partitions, but it takes up the permanent stretching or lengthening which would inherently result from constant opening and closing of the files.

Numerous variations may doubtless be devised by persons skilled in the art without departing from the principles of my invention. I, there-

fore, desire no limitations to be imposed on my invention, except such as are indicated in the appended claims.

What I claim is:

5. 1. A filing device comprising a container open at its upper side, flexible means mounted in said container and extending the length thereof, a partition in said container mounted in slidable frictional contact with said flexible means, and means adjustably connected to said flexible means for increasing the frictional contact between said flexible means and partition to impede the progressive movement of said partition and prevent accidental displacement. 5
10. 2. A filing device comprising a container open at its upper side, flexible means mounted in said container extending the length thereof, a plurality of partitions in said container mounted in slidable frictional contact with said flexible means, and means adjustably connected to said flexible means to vary the frictional contact between said flexible means and partitions by angularly displacing portions of the flexible means in relation to the remainder thereof. 10
15. 3. A filing device comprising a container open at its upper side, parallel flexible strips extending the length of said container, a plurality of partitions mounted in slidable frictional contact with said strips, and means to angularly displace portions of the strips at a point beyond said partitions for varying the frictional contact between said strips and partitions to control the progressive movement of said partitions and prevent accidental displacement. 15
20. 4. A filing device comprising a container open at its upper side, a flexible strip extending the length of said container, a plurality of partitions mounted in slidable frictional contact with said strip, and means adapted to angularly displace a portion of the strip in relation to the remainder thereof to vary the tension of said strip and its frictional contact with said partitions. 20
25. 5. A filing device comprising a container open at its upper side, longitudinally extending supporting means at opposite sides of the container, a partition in said container slidably suspended on said supporting means transversely of said container, flexible means in said container extending the length thereof, said partition mounted in slidable frictional contact with said flexible means, and means to vary the frictional contact between said flexible means and partition by angular displacement of a portion of said flexible means in relation to the remainder thereof. 25
30. 6. A filing device comprising a container open at its upper side, longitudinally extending supporting means at opposite sides of the container, a plurality of partitions in said container slidably suspended on said supporting means transversely of said container, substantially parallel flexible strips extending the length of said container, at least one of the outermost of said partitions mounted in slidable frictional contact with said strips, and means for angularly displacing portions of said strips with relation to the remainder thereof to vary the frictional contact between said strip and partitions. 30
35. 7. A filing device comprising a container open at its upper side, longitudinally extending supporting means at opposite sides of the container, a plurality of partitions in said container slidably suspended on said supporting means transversely of said container, substantially parallel flexible strips extending the length of said container, at least one of the outermost of said partitions mounted in slidable frictional contact with said strips, and means for increasing the frictional contact between said strips and partitions. 35
40. mounted in slidable frictional contact with said strips, a spreader strip adapted to be inserted between said flexible strips to angularly displace portions of said flexible strips in relation to the parallel portions thereof and increase frictional contact between said strips and the outermost partition to progressively impede the movement of said partitions in said container. 40
45. 8. A filing device comprising a frame member having two substantially parallel and horizontal supporting members, a plurality of partitions transversely and slidably suspended from said supporting members, substantially parallel flexible strips secured at the ends thereof to said frame member and extending through said partitions in frictional contact therewith, and means to angularly displace portions of said flexible strips with relation to the remainder thereof to vary the frictional contact between said strips and partitions. 45
50. 9. A filing device comprising a frame member having two substantially parallel and horizontal supporting members, a plurality of partitions transversely and slidably suspended from said supporting members, substantially parallel flexible strips secured at the ends thereof to said frame member and extending through said partitions in frictional contact therewith, and means to angularly displace portions of said flexible strips at a point beyond said partitions and to vary frictional contact between said strips and partitions. 50
55. 10. A filing device comprising a container, a frame member arranged in said container having two substantially parallel and horizontal supporting members, a plurality of partitions transversely and slidably suspended from said supporting members, substantially parallel flexible strips extending through said partitions in frictional contact therewith, the strips being secured at one end to the frame and at the other to the container, and means to angularly displace portions of said flexible strips at a point beyond said partitions and to vary the frictional contact between said strips and partitions. 55
60. 11. A filing device comprising a container, a frame member arranged in said container and having two substantially parallel and horizontal supporting members, a plurality of partitions transversely and slidably suspended from said supporting members, substantially parallel flexible strips extending through said partitions in frictional contact therewith, the strips being secured at one end to the frame and at the other to the container, and means carried by said container for progressively angularly displacing portions of said flexible strips at a point beyond said partitions and to vary the frictional contact between said strips and partitions. 60
65. 12. A filing device comprising a frame member having two substantially parallel and horizontal supporting members, a plurality of partitions transversely and slidably suspended from said supporting members, substantially parallel flexible strips secured at the ends thereof to said frame member and extending through said partitions in frictional contact therewith, a spacer strip secured to one end of said frame member adapted to be inserted between the flexible strips to angularly displace portions of the same in relation to those portions of the strips passing through the partitions, and means on said spacer strip for progressively increasing or decreasing the frictional contact between said flexible strips and partitions. 65
70. 75. 75

13. A filing device comprising a frame member having two substantially parallel and horizontal supporting members, a plurality of partitions transversely and slidably suspended from said supporting members, substantially parallel flexible strips secured at the ends thereof to said frame member and extending through said parti-

tions in frictional contact therewith, elastic connectors between said partitions, and means carried by said frame adapted to angularly displace portions of said flexible strips with relation to the remainder thereof to vary frictional contact between said strips and partitions. 5
